UNITED STATES PATENT OFFICE.

JOHN HAMILTON SMELZER, OF WESTMOUNT, QUEBEC, CANADA.

GEARING.

997,422.

Specification of Letters Patent. Patented July 11, 1911.

Original application filed June 5, 1909, Serial No. 500,350. Divided and this application filed August 18, 1909. Serial No. 513,451.

To all whom it may concern:

Be it known that I, JOHN HAMILTON SMELZER, of the city of Westmount, in the Province of Quebec, Canada, have invented 5 certain new and useful Improvements in Gearing; and I do hereby declare that the following is a full, clear, and exact description of the same.

My invention relates particularly to means 10 for driving the brushes of a middlings purifier whereby the screens are kept clean, and it has for its object to provide means effecting an improved operative connection between a reversing screw shaft and a member 15 for reciprocating such shaft, this application being a divisional part of an application filed by me on June 5, 1909 under Serial No. 500,350, and which issued to Patent No. 984,307 granted Feb. 14, 1911. 20 The invention may be said to consist of the construction and arrangement of parts hereinafter described and pointed out in the claim.

For full comprehension, however of my 25 invention reference must be had to the accompanying drawings forming a part of this specification, in which similar reference characters indicate the same parts and wherein—

30 Figure 1 is an end elevation partly in section of my improved gearing; Fig. 2 is a side elevation thereof, also partly in section; Fig. 3 is a transverse sectional view taken on line B B Fig. 1; and Fig. 4 is a 35 bottom plan view of the gearing.

My improved gearing comprises a bearing *e* formed integrally with a head *f* movably mounted upon a shaft *g* adapted to be rotated by suitable means, not shown. 40 This shaft is formed with a double thread *i* the ends whereof at each end of the shaft are taken around the shaft and joined to form a continuous path leading back and forth. The head engages the threads of 45 the shaft by means of an oscillatory key carried thereby, the head being provided with an opening or key passage leading from the exterior thereof to the shaft and being of sufficient size to permit of the key 50 being passed therethrough in order that such key may be readily removed and re-

placed when desired, as in the event of the key breaking, means being provided for removably supporting the key in position engaging the threads of the shaft. 55

As shown here I prefer to make the head *f* with a downwardly extending boss *j* adapted to accommodate the stem *m* of an oscillatory key having a segmental feather *k* engaging the threads *i* of the shaft, the 60 head being formed with an opening leading from the bottom of the boss to the shaft *g*, the lower portion of the opening being of substantially circular form and having lateral extensions *k'* adapted to accommodate the ends of the feather when the key is being inserted or withdrawn, while its upper portion is enlarged as at *k*² to permit of oscillation of the key. Shoulders *k*³ formed at the inner ends of the passages 65 limit the movement of the key into engagement with the threads of the shaft and prevent the feather being pressed too tightly thereagainst.

The key is held in place by means of a 70 bushing *n* located in the circular portion of the key passage and encircling the stem *m* while the feather rests freely on the top thereof, a set screw *o* threaded into the 75 side of the boss and bearing against the bushing being employed to removably secure the bushing in position.

What I claim is as follows:

The combination with a shaft, having a 80 double thread, of a head slidably mounted 85 upon the shaft and having a downwardly projecting boss, such head being formed with a vertical key passage leading from the bottom of the boss to the shaft, the lower portion of the said passage being of 90 substantially circular form and having oppositely disposed lateral extensions adapted to accommodate a key feather, said head being also formed to present a shoulder adjacent the said passage, an oscillatory key 95 located within the said passage and comprising a segmental feather engaging the thread of the shaft and a stem disposed within the said boss, the movement of the key into engagement with the thread of the 100 shaft being limited by said shoulder, a bushing located within the cylindrical portion

of the passage and loosely encircling the stem of the key and adapted to have the feather resting freely on the top thereof, and a set screw threaded through the side 5 of the said boss and bearing against the bushing, for the purpose set forth.

In testimony whereof, I have signed my

name to this specification, in the presence of two subscribing witnesses.

JOHN HAMILTON SMELZER.
